UNITED STATES PATENT OFFICE.

HEBRON B. LAYMAN, OF NEW YORK, N. Y.

INTERNAL-COMBUSTION ENGINE.

1,176,299.

Specification of Letters Patent.

Patented Mar. 21, 1916.

Application filed June 30, 1914. Serial No. 848,138.

To all whom it may concern:

Be it known that I, HEBRON B. LAYMAN, a citizen of the United States, and residing at New York, in the county of New York and State of New York, have invented certain new and useful Improvements in Internal-Combustion Engines, of which the following is a specification, such as will enable those skilled in the art to which it appertains to make and use the same.

This invention relates to explosion or internal combustion engines, and particularly to engines of this class of the sleeve valve type, and the object thereof is to improve the construction of, and the method of assembling the parts of, engines of this class so as to facilitate the finishing and assembling of said parts and render the same more practical and economical without decreasing in any way the efficiency of said engines; a further object being to improve the water circulating system whereby the temperature of the parts of said engines as are apt to become overheated may be maintained at as low a degree as possible; and with these and other objects in view the invention consists in the construction, combination and arrangement of parts hereinafter described and claimed.

My present improvement is applicable to engines of the class specified, comprising any desired number of units or cylinders, and said invention is fully disclosed in the following specification, of which the accompanying drawing forms a part, in which the separate parts of my improvement are designated by suitable reference characters in each of the views, and in which:—

Figure 1 is a central vertical section through one unit or cylinder of an engine involving my invention; and, Figs. 2 and 3 similar views showing modifications.

In carrying my invention into effect the cylinder *a* is provided with an extension *a*² forming an explosion head within which is the explosion chamber *a*³ and, in practice, said cylinder and its explosion head are formed integrally and are passed upwardly through the bottom of the main outer casing or jacket *b*, and said main outer casing or jacket is provided with an inwardly directed member or members *b*², and the cylinder *a* with an outwardly directed member or members *a*⁴ which abut against the members *b*². The main outer casing or jacket *b* is provided at the top thereof with an enlargement

*b*³ within which are the inlet and exhaust manifolds *b*⁴ and *b*⁵, and said inlet and exhaust manifolds *b*⁴ and *b*⁵ are provided with inlet and exhaust ports or passages *b*⁶ and *b*⁷ which communicate with the explosion chamber *a*³.

The inlet and exhaust ports or passages *b*⁶ and *b*⁷ are controlled by a sleeve valve *c* mounted in an annular chamber *c*² formed by an annular casing *c*³, the outer wall *c*⁴ of which is formed integrally with the casing or jacket *b* and the inlet and exhaust manifolds *b*⁴ and *b*⁵, and the inner wall *c*⁵ of which is formed integrally with the explosion head *a*² of the cylinder or constitutes a part thereof.

The cylinder and its explosion head and the outer casing or jacket *b*, or the enlarged part *b*³ thereof, are provided with a detachable cap *d* which extends the full length of the engine and applies to all the cylinders thereof, and within the outer casing or jacket *b* is a water passage or chamber *e* which also incloses the manifolds *b*⁴ and *b*⁵, and the outer side or wall of the valve chamber and the water chamber or passage *e* is in communication with the cap *d* through ports or passages *e*².

Between the explosion chamber *a*³, or the walls thereof, and the inner wall *c*⁵ of the valve chamber is a water chamber or passage *f* which is in communication with the water chamber or passage *e* at the bottom of the valve casing as shown at *f*², and the water chamber or passage *f* incloses the top wall of the explosion chamber *a*³, except at the center thereof where there is a transverse member *g* provided with a threaded aperture *g*² in which the spark plug, not shown, is secured. The water chamber or passage *f* is also in communication with the cap *d* through ports or passages *f*³ and formed in

the cap *d* and in the top of the explosion head of the cylinder is a tubular or other chamber or recess *h* to receive the spark plug. In the accompanying drawing, I have also shown a piston *i* within the cylinder *a*, but it will be understood that the piston forms no part of this invention. I have also not shown the means for operating the valve *c* but it will be understood that any known or suitable means may be employed for this purpose. In the accompanying drawing, the explosion head *a*² is also shown of approximately the same transverse dimensions as the cylinder, but my invention is not limited

to this detail of construction, all that is necessary being that the said explosion head be of such dimensions as to permit of its being passed upwardly through the jacket or casing *b* in the operation of assembling parts of the engine.

With the construction herein described, the cooling water is admitted at the bottom, or near the bottom of the casing or jacket *b*, through an inlet at *j*, and said water passes upwardly between the outer casing or jacket *b* and the cylinder and both inside and outside of the valve chamber, or the walls thereof, and into the cap *d* from which it flows to the radiator in the usual manner, and then back to the inlet *j*, and there is a continuous upward flow of water both inside and outside of the valve casing, or on both the inner and outer walls thereof and between the said valve casing and the explosion chamber *a*³, or the walls thereof. This method of construction in which the valve casing consists of separate parts formed in connection with the explosion head and with the jacket or casing *b* facilitates the machining and finishing of the walls of the valve chamber as will be readily understood, and the improvement whereby the cylinder and its explosion head is passed upwardly into the inclosing jacket or casing also facilitates the assembling of the separate parts of the engine and renders the same more effective and economical.

In Fig. 2 of the accompanying drawing, the outer casing or jacket *b*, the cap *d* and the inlet and exhaust manifolds *b*⁴ and *b*⁵ together with the outer wall *c*⁴ of the valve chamber or casing and the valve *c* are all the same as in Fig. 1. In this construction, however, the explosion chamber *a*³ is enlarged transversely and extends only just above the inlet and exhaust ports or passages *b*⁶ and *b*⁷ of the manifolds *b*⁴ and *b*⁵, and the bottom of the chamber or recess *h* into which the spark plug is passed extends downwardly below the inlet and exhaust ports or passages *b*⁶ and *b*⁷ into the explosion chamber, and around the bottom walls *h*² of said chamber or recess is a water chamber *f*⁴ which is in communication with the cap *d* through the ports or passages *f*³, the same as in Fig. 1, but the water chamber *f*⁴ is not in communication with the water chamber or passage *e* which incloses the cylinder and its explosion head, but the inner wall *c*⁵ of the valve chamber in this construction, is formed integrally with the explosion head as in Fig. 1, and the cylinder *a* with its explosion head is passed upwardly through the outer casing or jacket *b*, in assembling the parts of the engine the same as with the construction shown in Fig. 1. With this construction there is no circulation or passage of water up through the explosion head and on the inner side of the valve casing, or the walls

thereof, but the water flows upwardly freely between the cylinder and the jacket *b* and around the manifolds *b*⁴ and *b*⁵, and into the cap *d*, and the water in said cap is also free to flow down into the chamber or passage *f*⁴ in the top portion of the explosion chamber and back up into said cap from which it passes to the radiator. It will therefore be seen that the main difference between the construction shown in Figs. 1 and 2 is that the valve casing is water-jacketed on both its inner and outer sides in Fig. 1, and the water flows upwardly on both the inner and outer sides of the walls of said valve casing, while in Fig. 2 there is an upward flow of water only on the outer side of the valve casing or chamber and water is free to flow downwardly from the cap *d* into the explosion head and within the top walls of the valve casing or chamber.

In the construction shown in Fig. 3, the main outer casing or jacket *b* extends only to, or slightly above the top of the cylinder *a*, where it connects with the valve casing *c*³, the outer wall *c*⁴ of which is formed integrally therewith, as shown in Figs. 1 and 2, and the inner wall *c*⁵ of which is formed integrally with the explosion head of the cylinder. In this form of construction, the explosion chamber *a*³ is approximately similar to that shown in Fig. 1, and there is a water chamber or passage *f*⁵ between the explosion chamber or the walls thereof, and the inner wall *c*⁵ of the valve chamber or casing, and said water chamber or passage *f*⁵ is in communication with the main chamber or passage *e* at the bottom of the valve chamber or casing as shown at *f*², and the same as in Fig. 1, and said water chamber or passage *f*⁵ is in communication with the cap *d* through the ports or passages *f*³ as in Fig. 1. With this construction the valve chamber or casing is not water-jacketed on its outer side and the inlet and exhaust manifolds *b*⁴ and *b*⁵ are also not water-jacketed, but there is a constant flow of water up through the water chambers or passages *e* and *f*⁵ around the cylinder and through the explosion head and on the inner side of the valve chamber or casing.

In all the forms of construction shown, the valve casing and valve is entirely above, or beyond the limit of the movement of the piston, but this is not absolutely necessary, and changes in and modifications of this feature of construction as well as others herein shown and described may be made, within the scope of the appended claims, without departing from the spirit of my invention or sacrificing its advantages.

Having fully described my invention, what I claim as new and desire to secure by Letters Patent, is:—

1. In an explosion engine, a cylinder having an extension forming an explosion head

containing an explosion chamber, said cylinder being inclosed by a main outer casing or jacket provided at the top thereof with a cylindrical supplemental casing with which the inlet and exhaust manifolds are connected and into which the explosion head of the cylinder is insertible from the bottom thereof, said explosion head and said supplemental casing forming an annular valve 5 casing adapted to receive a sleeve valve which controls the inlet and exhaust ports of the explosion head, and said main outer casing or jacket being enlarged at the top thereof to inclose the inlet and exhaust 10 manifolds and the valve casing and to form a main water chamber or passage inclosing said parts, and said explosion head being provided within the valve casing with a supplemental water chamber or passage in 15 communication with the main water chamber or passage below the valve casing, and said main water chamber or passage and supplemental water chamber or passage being provided with outlets at the top of the 20 engine.

2. In an explosion engine, a cylinder having an extension forming an explosion head containing an explosion chamber, said cylinder being inclosed by a main outer casing or jacket provided at the top thereof with a cylindrical supplemental casing with which the inlet and exhaust manifolds are connected and into which the explosion head of the cylinder is insertible from the bottom 30 thereof, said explosion head and said supplemental casing forming an annular valve casing adapted to receive a sleeve valve which controls the inlet and exhaust ports of the explosion head, and said main outer 35 casing or jacket being enlarged at the top thereof to inclose the inlet and exhaust manifolds and the valve casing and to form a main water chamber or passage inclosing said parts, and said explosion head being provided with the valve casing with a supplemental water chamber or passage in 40 communication with the main water chamber or passage below the valve casing, said main water chamber or passage and supplemental 45 water chamber or passage being provided with outlets at the top of the engine, and said engine being also provided at the top thereof with a detachable cap with which said outlets communicate.

3. In an explosion engine, a cylinder provided with an integral extension forming an explosion head containing an explosion chamber, and a main outer casing or jacket inclosing the cylinder and the explosion 55 head and provided with a supplemental casing with which the inlet and exhaust manifolds are connected and into which said explosion head is adapted to be inserted from the bottom thereof and which forms in connection with said explosion head an annular

valve casing adapted to receive a sleeve valve which controls the inlet and exhaust ports, and said explosion head being provided around the explosion chamber and inwardly of the valve casing with a water 70 chamber or passage in communication below the valve casing with a main water chamber or passage which incloses the cylinder and manifolds, and said engine being also provided with a detachable cap with which said 75 water chambers or passages are in communication.

4. In an internal combustion engine, a main outer casing or jacket, a cylinder inserted therewith and forming in connection therewith a main water chamber or passage, said cylinder being extended to form an explosion head, and said main outer casing or jacket being provided with an extension with which the manifolds are connected and 80 which forms in connection with said head a sleeve valve chamber which incloses said head, and said head being provided inwardly of the sleeve valve chamber with a supplemental water chamber or passage 85 which is in communication with the main water chamber or passage below said valve chamber.

5. In an internal combustion engine, a main outer casing or jacket, a cylinder inserted therewith and forming in connection therewith a main water chamber or passage which incloses said cylinder, said cylinder being extended to form an explosion head, and said main outer casing or jacket being 90 extended to inclose said head and a sleeve valve chamber inclosing said head and formed partly thereby and partly by the main outer casing or jacket.

6. In an internal combustion engine, a main outer casing or jacket, a cylinder inserted therewith and forming in connection therewith a main water chamber or passage which incloses said cylinder, said cylinder being provided with an extension forming 100 an explosion head, and said main outer casing or jacket being provided with an extension with which the inlet and exhaust manifolds are connected and which forms in connection with said head a sleeve valve 105 chamber and a detachable cap placed on said head and the extension of the main outer casing or jacket, said explosion head being also provided with a supplemental water chamber or passage which is in communication with the main water chamber or passage and which is also in communication with the detachable cap.

7. In an internal combustion engine, an outer casing, a cylinder inserted therewith and forming in connection therewith a main water chamber or passage, said cylinder having an explosion head, a sleeve valve chamber between and formed by said casing and said head, and said head being provided 120

inwardly of the sleeve valve chamber with a supplemental water chamber or passage which is in communication with the main water chamber or passage below said valve 5 chamber.

8. In an internal combustion engine, a main outer casing, a cylinder inserted thereinto, and provided with an explosion head, a water chamber formed by the outer casing 10 and the cylinder, and a sleeve valve chamber formed by and between the explosion head and the casing, said head being provided inwardly of the sleeve valve chamber with a water chamber or passage.
9. In an internal combustion engine, a main outer casing, inclosing the intake manifold, a cylinder inserted thereinto and provided with an explosion head, a water chamber formed by and between the said casing 15 and cylinder, and a sleeve valve chamber formed by and between the explosion head and the casing.
10. In an internal combustion engine, a

main outer casing, inclosing the exhaust manifold, a cylinder inserted thereinto and 25 provided with an explosion head, a water chamber formed by and between the said casing and cylinder, and a sleeve valve chamber formed by and between the explosion head and the casing.

11. In an internal combustion engine, a main outer casing, inclosing the intake and exhaust manifolds, a cylinder inserted thereinto and provided with an explosion head, a water chamber formed by and between the 30 said casing and cylinder, and a sleeve valve chamber formed by and between the explosion head and the casing.

In testimony that I claim the foregoing as my invention I have signed my name in 40 presence of the subscribing witnesses this 25th day of June 1914.

HEBRON B. LAYMAN.
